UNITED STATES PATENT OFFICE.

EDWARD A. MUCKLE, OF ROCKFORD, ILLINOIS.

MAGIC WATCH-CASE.

SPECIFICATION forming part of Letters Patent No. 275,251, dated April 2, 1883.

Application filed August 5, 1882. (No model.)

To all whom it may concern:

Be it known that I, EDWARD A. MUCKLE, a citizen of the United States, residing in the city of Rockford, in the county of Winnebago 5 and State of Illinois, have invented new and useful Improvements in Watches, of which the following is a specification.

My invention relates more particularly to the cases inclosing the movement; but especially to 10 that class of watch-cases known as the "magic case."

The object of my invention is to improve the magic watch-case to render it capable of a complete mechanical construction, by which a desirable article may be produced at a moderate 15 cost adapted to incase both stem and key winding watches; and it consists in supporting the inner or movement-containing case to revolve on pivotal centers; in providing a pusher to 20 perform the several functions, as follows: as a pivot on which the inner or movement-containing case revolves; as a pusher to disengage the case-holding spring; as the key in a stem-winding watch, and as a key to rotate the inner or movement-containing case in key-winding 25 watches.

It further consists in supplying a suitable backing to the pusher to produce a dust and water proof movement-containing case, all of 30 which will be hereinafter more fully described.

In the accompanying drawings, Figure 1 is 35 a plan view of a watch-case embodying my invention. Fig. 2 is an elevation. Fig. 3 is a transverse central section on dotted line *x* of the closed case employed as an open-face case. Fig. 4 is a transverse central section on dotted line *x* of the closed case employed as a hunting-case. Fig. 5 is a central section on dotted line *y* of the case as a stem-winder. Fig. 6 is 40 an isometrical representation of the pusher as a stem-winder. Fig. 7 is a central section on dotted line *y* of the case as a key-winder. Fig. 8 is an isometrical representation of the pusher as a key-winder.

45 In the figures, A represents the central rim portion of the outer case of the watch. This rim is of the usual form, and is provided with a pendant, *a*, securely fixed thereto and projecting outward.

50 At *b* is represented the pendant-ring, having its end portions pivoted in the pendant *a*.

At B is represented the metallic back of the outer case, which, when the case is employed as a hunting-cased watch, is the portion there-

of which covers the crystal-case employed to 55 protect the dial-face of the watch. This portion of the case is hinged to the central rim, A, at a point opposite the pendant.

At *c* is represented a spring fixed in the center rim of the case, having its free end engage 60 the hinged case at or near the point of its hinged connection with the center rim in such a manner that its spring action will tend to open the case.

At *d* is represented the detent-spring, fixed 65 in the center rim of the case, having its free detent end adapted to engage the free edge of the case when closed at or near the pendant.

At C is represented an open-rim case, hinged 70 to the center rim, A, at the side thereof opposite the pendant, and it is fitted to engage the rabbeted edge of the central rim snugly, producing a close-fitting joint. This rim-case is designed to close snugly over the crystal-covered 75 face of the watch when employed as an open-faced watch, and over the back casing of the inner or movement-containing case when employed as a hunting-cased watch.

At *e* is represented a pivot-supporting plate 80 suitably fixed in the inner edge of the center rim of this outer case at a point exactly opposite the pendant. This plate is provided with a central opening to receive a pivot-stud projecting outward from the central rim of the inner case.

At *h* is represented the central rim of the inner case, having its edges rabbeted to receive side cases.

At *i* is represented a metallic back, which is 85 fitted to engage one of the rabbeted edges of the central case snugly, producing a close-fitting dust and water tight joint.

At *k* is represented a rim-case fitted to receive a crystal-plate, *l*, in a manner to produce a dust and water tight joint. This rim-case in 90 this instance has a hinge-joint connection with the center rim, and is fitted to engage the rabbeted edge thereof in a manner to produce a joint-connection proof against the admission of dust or water. This case is designed to 95 contain the watch-movement with its dial-face under the crystal-case, and this case is of proper dimensions to enter within the center rim of the outer case, and its center rim is provided on one side with a pivot-stud, *m*, fitted 100 to enter the opening in the pivot-supporting plate *e*. The pendant of the outer case is provided with a suitable axial opening; and the 105

detent-spring *d* and the center rim of the inner case are also provided with suitable holes or openings in line with the axial openings in the pendant.

5 At *E* is represented the outer head end of the pusher, which is of spherical outline, having a stem portion, *n*, fitted to enter the outer enlarged portion of the axial opening in the pendant, and the head portion is provided with 10 an annular groove, *n'*, to receive the outer end portion of the pendant. This stem portion *n* is provided with an annular groove, *o*, which receives the inner end portion of a screw, *p*, passed through the wall of the pendant. 15 The construction and arrangement of annular groove *o* and screw *p* are such as to permit of a limited endwise movement of the pusher.

At *r* is represented a shaft-like portion, which, in this instance, has a screw-connection 20 with the head portion of the pusher. This central portion, *r*, of this shaft is fitted to slide endwise in the inner portion of the pendant, and the portion *r'* of its inner end is reduced to pass through the detent-spring, forming a 25 shoulder to engage the outer surface thereof in such a manner that an inward pressure on the head of the pusher will force the free end of the detent-spring inward and disengage it from the metallic back *B*, permitting it to be 30 thrown open by the action of the case-spring *c*. The inner end of this reduced portion *r'* of the shaft is passed through the central rim portion of the inner case, and serves as one of the pivots on which the inner case is mounted, 35 and, in connection with the pivot-stud *m*, supports the inner case in a manner to permit it to be turned on its pivotal supports within the outer case to present the crystal-covered dial-face to either side of the outer case, producing 40 a movement-containing case mounted on pivotal supports within the outer case and capable of use either as an open-face or hunting-cased watch. The portion *r''* of this shaft, extending within the inner case, is produced in 45 this instance rectangular in section, adapted to engage the winding mechanism of the watch, producing a stem-winder. This connection of the shaft with the winding mechanism is such that when it is used as a pusher it will slide 50 endwise without interfering with the movement or winding mechanism.

From the foregoing it will be seen that in my improvements the pusher serves the purpose of a pusher to disengage the detent-spring 55 to permit the metallic back of the case to open, as a pivot-support to the inner case, on which it may be turned to change the watch from an open-face to a hunting-cased watch, or vice versa, and as a key to the stem-winding mechanism to wind the watch.

At *s* is represented a packing, which may be of any suitable material—such as leather, felt, cork, or other material adapted to the purpose—and which is employed to surround the 60 stem of the pusher inside of the inner case, and is held in position by means of a suitable plate, *s'*, fixed to the inner walls of the inner

case. This packing serves to exclude dust and to prevent even water from entering the case at this point, and, in connection with the close-fitting case, enables me to produce a dust and water proof watch-case.

In the application of my improvements to key-winding watches I produce the inner end, *t*, of the pusher in rectangular form in section, 75 and provide the inner case with a hole of like form to receive it, which furnishes the means by which the inner case can be turned within the outer case by rotating the head of the pusher.

I am aware that a watch-case known as the 80 "magic watch-case" has been produced prior to my invention, and that such case consisted of an outer case, composed of a center rim-case, a closed metallic back, and a metallic ring-case hinged to opposite sides of the 85 central rim-case, and that said case was provided with a case-spring, and with a spring-detent to engage the metallic back, and that said case contained an inner movement-containing case capable of being turned within the outer case, 90 to be used as a hunting-cased watch or as an open-faced watch. These therefore, as such, I do not claim; but

I claim as my invention—

1. The outer case having the pendant rigidly connected to the rim thereof, a pusher extending through said pendant and capable of an axial movement therein, in combination with an inner or movement-containing case adapted to be turned within the outer case, 100 substantially as and for the purpose set forth.

2. A pusher capable of an axial movement in the pendant of the outer case, in combination with an inner or movement-containing case, said pusher forming one of the pivots 105 upon which the inner or movement-containing case may turn, substantially as and for the purpose set forth.

3. The combination, with the pusher and with the movement-containing case pivoted 110 thereto, of the packing *s*, surrounding the stem of the pusher within the movement-containing case, to prevent the admission of dust or water thereto, as set forth.

4. The combination, with the detent-spring 115 of the outer case and with the movement-containing case, of a pusher capable of a limited axial movement to depress the detent-spring, and forming one of the pivots upon which the movement-containing case may turn, substantially as and 120 for the purpose set forth.

5. The combination, with the pendant, the spring-detent, and the movement-containing case, of a pusher capable of a limited axial movement in the pendant, said pusher adapted 125 to depress the detent-spring, and having a pivotal connection with the movement-containing case, and the inner end adapted to engage the winding mechanism of a movement contained within the case, substantially as and 130 for the purpose set forth.
